UNITED STATES PATENT OFFICE

ELLWOOD WALTER ROBERTS, OF GERMANTOWN, PENNSYLVANIA

SHOE RACK

Application filed January 8, 1930. Serial No. 419,331.

My invention relates to certain improvements in racks particularly adapted for use in homes for properly holding shoes.

One object of my invention is to make the device collapsible, so that it can be packed into a small compass when traveling.

A further object of the invention is to arrange the rack in a number of identical sections, one suspended from another. The length of the rack can be increased by adding additional sections when desired.

A still further object of the invention is to so arrange the rack that each section will hold one pair of shoes.

In the accompanying drawings:

Fig. 1 is a perspective view of the rack, showing two sections;

Fig. 2 is a side view of the rack, showing three suspended sections, the upper section being hung from a nail or other support on the wall or door;

Fig. 3 is a detached face view of one of the sections;

Fig. 4 is a detached side view of one of the pivoted members; and

Figs. 5 and 6 are views illustrating modifications of the invention.

Referring to the drawings, 1 is a section of a shoe-supporting rack made in one piece of wire bent into shape and having a central loop suspending portion 2 which also acts as a division between a pair of shoes hung on the rack.

3 are the horizontal portions on which the heel end of a shoe is mounted, and the outer ends of these horizontal portions are looped portions 4 which prevent the shoe being dislodged from its support. These 40 projections may also be used to suspend other articles if desired.

A vertical member 5 extends from each looped portion 4 downwards. The lower end of this member is in the form of a hook 6 from which another section is suspended by its looped portions 4 as clearly shown in Fig. 1. Some distance above the hook section is a pivot 7 made by bending the wire into the form of an S-loop, a portion 8 of the loop forming trunnions on

which the transverse member 9 is mounted.

The pivoted member 9 is U-shape in form and consists of side members 10 and a cross-bar 11 which supports the toe ends of the shoes as shown in Fig. 2. At the junction of the side members and the cross-bar are upwardly extending loops 12 which form stops to prevent lateral displacement of the shoes.

Each side member is bent to form a bearing 13. These bearings are mounted on the trunnions 8 of the section 1. The portion of the pivoted member that extends rearwardly beyond the trunnions holds each section away from the wall *a*, Fig. 1. Each side member of the pivoted member is bent back of the bearing as at 18 and prevents the said member swinging in one direction on the trunnions.

The bearing 13 is made by twisting the wire into the form of an eye as shown in Figs. 1 and 4, but the bearing may be formed as shown in Fig. 6, in which the bearing 13a is formed by bending the wire to form an eye which can be passed over the trunnions. The bearing may also be formed in the side members 5a of the section 1a by bending the section into the form of a loop, and the pivoted member may be bent laterally to form an offset member 14, 80 which not only forms the trunnion 8a but also a stop 16 which bears against each side member 5a when in horizontal position, as shown in Fig. 5.

When the support for the rack is of sufficient length, then all of the sections are in a vertical plane, and the pivoted members are in a horizontal plane, but if the support projects only a short distance from the wall, then the upper section is arranged at an 90 incline and its transverse member will be on a slight incline as in Fig. 2.

It will be seen by the above description that such a shoe rack can be made very cheaply, as each of the two parts of each section is made by bending wire into form, and the sections can be readily hung one from another to any length desired, and the pivoted members hold each section of the rack the proper distance away from the wall 100

or door on which the rack is hung, so as to provide sufficient room for the heels of the shoes as shown by dotted lines in Fig. 2, and as the pivoted member of each section is pivotally hung to the main section, the rack can be readily folded so as to take up a comparatively small space in shipping or when packed in a traveling bag.

I claim:

10. The combination in a shoe rack, of a series of identical sections, one section being loosely hung from another section; and a pivoted member mounted on each section, said pivoted member having rearwardly extending arms arranged to rest against the wall of the support and forwardly extending arms connected by a horizontal portion, each section also having a horizontal portion located back of the horizontal portion of the 15. pivoted member, said horizontal portions being arranged to support a shoe.
20. The combination in a shoe rack made in sections, each section comprising a vertical member having loops in the upper ends and having two vertical members; hooks at the lower end of each vertical member, from which another section can be suspended; a trunnion on each vertical member; a pivoted member having bearings mounted on the trunnions; and a cross-bar at the front of the pivoted member, some distance from the bearings, said cross-bar arranged to support the toe end of a shoe, said pivoted member having a rearward extension arranged to rest against the wall from which the rack is suspended, so as to hold the rack away from the wall.

25. The combination in a shoe rack made in sections, one section being suspended from another section, each section having two horizontal portions to support the heel ends of the shoes; a looped dividing member separating the two horizontal portions and looped end members for retaining a pair of 30. shoes in position, the vertical members of each section of the rack having hooks at their lower ends, from which another section can be suspended; a trunnion on each section; and U-shaped members pivotally mounted on the trunnions, said U-shaped members having cross-bars at the front for supporting the toe ends of the shoes, and having rearwardly extending portions which rest against the wall and hold the rack away from the wall.

35. The combination in a section of a shoe rack, made of wire, said section having two parts, one part having vertical members and a cross-bar, said cross-bar arranged to support the heel-ends of shoes and having means at the lower end of each vertical member from which another section of the rack is suspended; trunnions on the vertical members, the other member of the section of the 40. rack being U-shaped and pivotally mounted

on the trunnions of the first-mentioned member, said U-shaped member forming a cross-bar extending in front of the section of the rack and arranged to support the toe ends of the shoes; and a stop on the pivoted member to limit the movement of said pivoted member in one direction and allowing it to turn on the trunnions to the closed position when moved in the opposite direction.

5. The combination in a shoe rack, of a series of sections, one section being suspended from another and each section consisting of two parts made of wire, the main section having two vertical portions and a horizontal portion for supporting the heel end of shoes; a loop dividing said horizontal portion so as to separate the shoes and also acting as a means for suspending the upper section of the series from a support; side loop sections for preventing the shoes slipping of the support laterally, the looped sections having a rearward extension at the upper end, the vertical members having hooks at their lower ends, with which the loops of adjoining sections can engage; S-shaped trunnions on the vertical sections; a pivoted member U-shaped in form, the cross-bar at the outer end of the pivoted member supporting the toe ends of the shoes; an upwardly extending loop at each end of the cross-bar to prevent lateral displacement of the shoes on the cross-bar; and bearings on each pivoted member, mounted on the trunnions and arranged so as to form a stop to limit the downward movement of the cross-bar end of the pivoted member but allowing it to freely turn on the pivot when moved to its closed position.

ELLWOOD WALTER ROBERTS.
